CAN-BODY FLANGER.

1,049,663.

Specification of Letters Patent.

Patented Jan. 7, 1913.

Application filed February 3, 1910. Serial No. 541,889.

To all whom it may concern:

Be it known that we, FRANZ BRÜCKMANN, Jr., and OTTO DEMPEWOLF, residents of Brunswick, Germany, have invented certain new and useful Improvements in Can-Body Flangers, of which the following is a full, clear, and exact specification, such as will enable others skilled in the art to which it appertains to make and use the same.

10 Our invention relates to a development of the machine for flanging or otherwise operating on can bodies, which is set forth in the prior patent to Franz Brückmann, Jr., and Otto Dempewolf, dated August 4, 15 1908, No. 895067. In that prior patent and in the example of the invention given in this specification the machine is shown as organized for the purpose of forming flanges on the ends of the can bodies preparatory 20 to the application of the heads thereto. It may, however, be adapted to other operations without departing from the essential principle of the invention.

The present invention involves certain improvements in the general organism of the machine, in the construction and arrangement of the flanging heads which engage the ends of the can body during the operation of the flanging tool and coact therewith, in 25 the construction and arrangement of the chutes or devices by which the can bodies are fed to the flanging devices and in various other features of construction and combination of parts all of which will be 30 fully set forth hereinafter and particularly pointed out in the claims.

Reference is now had to the accompanying drawings, which as has been said, represent as an example the preferred embodiment of the invention, and in which drawings

45 Figure 1 is a sectional plan of the machine; Fig. 2 is a diagrammatic view showing the scheme of the machine and, illustrating among other things, the carrying on of four distinct operations simultaneously; Fig. 3 is an enlarged sectional view taken through the flanging heads and chute; Fig. 4 is a detail view of the flanging wheel of 50 which there may be either one or more than one in the machine; Fig. 5 is a view illustrating the movement of the can bodies through the chute; Fig. 6 is a sectional view 55 showing the flanging head when it first engages the can body; and Fig. 7 is a similar

view showing the movement of the anvil ring during the formation of the flange.

Preferably the machine is arranged with its rotating parts on horizontal axes which allows the can bodies to be fed by gravity 60 to the machine and avoids the use of devices for advancing them. As shown in the drawings, particularly Fig. 1, a suitable frame 10, is provided comprising two side members between which passes the main or 65 central shaft 11, the same being revolvably mounted and having at one end a spur wheel 12 or other devices for rotating it. This shaft 11 carries the flanging wheels 14 which are fast thereto to turn therewith, and 70 which will be described in detail hereinafter. In addition the shaft 11 carries cams 15 for operating the flanging heads. In each side 10 of the frame are mounted two rotary shafts 16. These shafts are opposite 75 each other in pairs and carry the flanging heads. The number of pairs of shafts 16 and the number of pairs of flanging heads depends upon the desired capacity of the machine and these parts might be 80 grouped around the periphery of the flanging wheels in any number within the limits of the size of the wheels. Thus, as shown in Fig. 2, four pairs of flanging heads may be provided, the positions 15 indicating the 85 four positions of such heads. The can chutes 17 are also, according to the construction shown in Fig. 2, four in number, corresponding respectively with the four pairs of flanging heads. In Fig. 1, for convenience, only two pairs of flanging heads are 90 illustrated. It should be understood of course that the invention is by no means limited to any specific number of pairs and flanging heads. When, however, the arrangement illustrated in Fig. 2 is employed, the efficiency of the machine is greatly increased, since it allows four cans to be flanged at the same time and, as will be seen hereinafter, by a single rotation of the 100 flanging wheels. Further, one or two flanging wheels may be employed, according as it may be desired to flange one or both ends of the can simultaneously.

The shafts 16 carrying the flanging heads 105 are provided with gears 18 at one side of the machine meshing with the upper gear 12. These gears 18 are splined on the shafts 16 so that the shafts may move in the gears but are forced to turn therewith. This axial 110

motion of the shafts 16, according to the construction illustrated, is brought about by levers 19 which are suitably articulated to the shafts 16, so that the rotation of the shafts will not be interfered with. At their opposite ends the levers 19 are articulated to links 20 which are joined to the frame; and intermediate their ends the levers 19 are connected by links 21, with the slides 22 which are mounted in the frame and provided with rollers 23 which run in the cams 15. This causes a periodic movement of the shafts 16 in and out, which movement is timed to take place in a certain relation to the flanging wheels as will hereinafter appear.

Fig. 3 illustrates the details of the flanging heads and their coacting parts. As is there shown the chute 17 carrying the can bodies *a* on which the flanges *a'* are to be formed is provided in its sides with openings 17^a. These openings are opposite each other and the coacting pair of flanging heads are arranged so that they will move through said openings into the chute. Each flanging head comprises a body 24 of form corresponding to the cross-sectional form of the can, which bodies have their hubs 25 fastened to the shafts 16 and their peripheries formed with shoulders 26 against which the flanges are bent. The flanging heads also embody, each of them, a frusto-conical centering plate or pilot 27, which is adapted to enter the can body and guide the same into proper engagement with the shoulder 26. At the inner side of the head 24 is arranged an anvil ring 28, which fits against the outer side of the centering plate 27 and is of a diameter equal to the diameter of the can and to the reduced portion of the head 24, formed by the shoulder 26. This anvil ring 28 is held as a floating member by means of a number of dogs 29 pivoted in the head 24 which is hollow to receive them and pressed by springs 30. Normally these dogs and springs hold the anvil ring 28 central and concentric to the head 24, but when the flanging device is in operation the springs give and allow the anvil ring to be thrown at an eccentric position as shown in Fig. 7. The instant that the pressure of the flanging tool is relaxed the springs 30 return the anvil ring to its normal or concentric position. When, therefore, the flanging heads move into the chute 17, under the action of the levers 19 and their coördinate parts, the pilot or guide plates 27 center the can body with respect to the anvil ring and head 24 and the continued movement of the heads causes the anvil ring 28 to enter the can body and the ends of the can body to engage the shoulders 26 at which time the movement of the flanging heads inward is arrested and such heads dwell in their inward position with the can engaged with them as shown in Fig. 6. At this time the flanging

wheels with their tools become operative and during the formation of the flange the anvil ring of the flanging head assumes the position shown in Fig. 7.

As has been pointed out, the flanging heads are arranged in pairs at stations around the periphery of the flanging wheels. These flanging wheels are provided on their peripheries with flanging tools which are shaped to perform the necessary operations on the ends of the can body to produce the flange. As shown in Fig. 4, the wheel has three flanging tools which are preferably fastened to the main part of the wheel and are of such material as may be suited to their work. These tools are shaped and of different widths so that the flanging wheel rotating in the direction of the arrow in Fig. 4 brings the tools 32, 33 and 34 successively into operation. In addition to said tools 32, 33 and 34 on the periphery of the wheel, said wheel is formed with a concentric segment 31 constituting the most reduced diameter of the flanging wheel and the parts are so timed that as the can body falls into position opposite the flanging heads the concentric portions 31 of the wheels 14 are opposite the can body, thus permitting free movement of the can into position. The flanging heads are then moved into engagement with the can and the tools on the flanging wheel brought successively into engagement with the can producing the flange thereon. As the portion 31 of the tool wheel approaches the flanged can in the revolution of the wheel, the heads are withdrawn from engagement with the can, which is discharged, and a second can body is brought into position. The flanging wheels lie in positions corresponding to the ends of the can body and as shown in Fig. 5 they pass through openings 17^b in the chutes 17 so that they may act on the cans.

The construction of the can chutes and the devices for controlling the movement of the cans is important and will now be described.

The can body chutes may extend from any point desired. For example, they may be directly connected with the can body former, *i. e.*, the machine which makes the can bodies and they may be made to carry superimposed any desired number of can bodies ready to be supplied to the flanging devices. It is found, however, that the can bodies in the lower part of the chute, bearing the weight of the superimposed cans, are caused to flatten by this weight and if the chute is of a size equal only to the diameter of the can bodies, such bodies would bind in the chute. To overcome this difficulty, we widen the chute at its lower portion in the manner indicated in Fig. 5, so that ample room is given for the can bodies to pass, notwithstanding the spreading or flattening

thereof. By thus widening the chute, however, a further difficulty is presented in that the can bodies might not be presented in proper position to the flanging devices. 5 This proper position is shown in Fig. 5 as opposite the opening 17^b. To overcome this secondary disadvantage we cause the lower end 17^c of the chute to be bent or turned away from the flanging wheel and the diameter of the chute contracted to approximately the diameter of the can, which being flanged, is less liable to spring or flatten. This insures that the can immediately below the one being flanged takes a position 10 outward from the position of the can being operated on. The result of this is that the can to be operated on is thrown inward toward the flanging wheel and therefore caused to take its proper position opposite 15 the flanging heads notwithstanding that the chute is wider than the cans. When the can body below the one being operated on is discharged from the chute, the flange body immediately above drops to the lower end 20 of the chute and the third can body then falls toward the flanging wheel and takes the place of the preceding body by reason of the curving sides thereof which throw the third or following body inward into 25 proper position.

In order to sustain the can bodies in the chute and also to allow them to fall from the same as fast as they have been operated upon, we provide the stop bars 35 shown in 30 Figs. 3 and 5. Said stop bars are arranged to enter the chute 17 through opening 17^a therein and they are mounted to slide horizontally in bearings 36 mounted on the frame sections 10 or otherwise. Said stop bars 40 are actuated by levers 37, the lower ends of which engage between lugs 38 fastened on the slide bolts or stops 35 and the upper ends of which engage the collars 39 fastened to move in synchronism with the shafts 16. 45 As the shafts 16 move inward to engage the flanging heads with the can body next to be acted upon, the stop bars 35 are, it will be seen, moved outward. At this time the flanging heads will hold the can body between them and the pile of cans in the chute 50 will thus be supported. Simultaneously the bolts 35 having been withdrawn the bottom-most body falls finished from the chute. The instant that the flanging heads are withdrawn, the bolts 35 are shot inward and as 55 the second finished can body falls from the flanging heads it is intercepted and supported by the bolts.

If desired, at the entry of the can bodies 60 into the chutes, they may be regulated to prevent too great a pile from entering the chute and hence to avoid an excessive pressure on the cans at the lower end thereof. This may be accomplished by stop bolts 40, 65 which, like the stop bolts 35, work and

out in the chutes. These stop bolts 40, however, should be arranged at the receiving ends of the chutes and may be operated automatically in any manner desired; for example by a linkage 40 driven through a rod 70 or other connection 42 from a cam race 43 on one of the wheels 14 or otherwise.

The organized operation of the machine may be traced as follows: The cans are supplied to the chutes and the operation of the machine started by applying primary power to any one of the shafts 11 or 16 through a band pulley thereon or in any other desired manner. Upon the rotation of the flanging wheels 14 the flanging heads are caused to move inward to engage the can body opposite them at the instant that the concentric portion 31 of the flanging wheel is opposite the opening 17^b in the chute 17, thus allowing a can body to fall into position while 80 said portion 31 of the flanging wheel is opposite the can body so that the can body will not be obstructed. The flanging heads approach each other until the can body assumes the position indicated in Fig. 6. At 85 this time the first flanging tool (32) on the wheel 14 moves into action striking the side of the can body directly opposite the anvil ring 28 and throwing this ring to eccentric position. This bends the can body down 90 over the inner edge of the flanging head 24 forming the flange as illustrated in Fig. 7. The flanging tools successively roll against the can body and successively form the various stages of the flange. During this time 100 the flanging head is rotating continuously and the anvil ring 28 bears inside of the can body snugly fitting against it so that the shape of the can body is retained and crushing of the same is avoided. The flanging 105 tools 32, 33 and 34 on the wheels 14 are of such a length that the circumference of the cans is equal to the length of each flanging tool so that each tool runs completely around the can and the entire circumference of the 110 can is therefore acted upon by each tool. As soon as the flanging operation is complete the wheel 14 again presents the surface 31 to the can, but since this surface does not contact with the can the springs 30 are permitted to return the anvil ring 28 to its concentric position. At this instant the flanging heads are withdrawn and the previously retracted stop bars 35 return to the chute with the result that as the flanged can falls 115 from the flanging heads it is engaged with and supported by the stop bolts so that the next following can strikes the curved top of the flanged can and rolls inward on said top to flanging position. The parts then assume 120 the relation shown in Fig. 6 and the above-described operation is repeated.

Having thus described our invention, what we claim as new and desire to secure by Letters Patent of the United States, is:

1. The combination of a wheel or disk having a plurality of tool surfaces on its periphery adapted successively to act on the work, means for mounting and rotating said member, a plurality of chutes leading the work to different points around the periphery of said member and means for holding the work during the operation of said tool surfaces thereon whereby a plurality of pieces of work may be simultaneously subjected to the action of said tool member.

2. In a machine for flanging can bodies, the combination of a shaft, a pilot member carried thereby, a head also carried by the shaft, an anvil ring surrounding the shaft between the head and pilot member, means for yieldingly sustaining the anvil ring and a flanging tool coacting with the anvil ring, the said means for mounting the anvil ring comprising dogs pivoted in the head and engaging the anvil ring and springs pressing the dogs, said springs being arranged radially within the head.

3. In a machine for manufacturing cans, the combination of a chute, tools entering the chute to act on the can, a stop bolt movable in and out of the chute below the tools to sustain the cans in the chute and a connection between the stop bolt and one of said tools to withdraw the stop bolt from the chute when said tool is in operation.

4. In a machine for manufacturing cans, the combination with the tool acting on the can, of a chute to receive the can bodies and lead them to said tool, said chute being provided with an aperture through which the tool has access to the can, the can bodies lying superimposed in the chute and the chute being wider at its lower portion than the diameter of the can bodies, for the purpose specified.

5. In a machine for manufacturing cans, the combination of a tool to act on the can

body, a chute to carry the can body to said tool, the chute being wider than the can bodies opposite the tool and a means below the tool for offsetting the can body at said point, whereby to cause the can body first-mentioned to roll laterally in the chute toward the tool.

6. In a machine for manufacturing cans, the combination of a tool adapted to act on the can body, a chute to conduct the can bodies to and away from said tool, said chute having an extension below the point of contact of the can with the tool, the wall of said extension adjacent said tool being inclined away from said tool, said chute being wider than the diameter of the can body and being provided below the point of engagement of the tool and can body with a movable stop bolt.

7. In a machine for flanging can bodies, the combination of flanger heads mounted to rotate and one of said heads movable axially, a flanging wheel coacting with one of said flanger heads, means for moving axially the said axially movable head and a cam on the flanger wheel to drive said means.

8. A machine for flanging can bodies comprising flanger heads mounted to rotate and to move axially toward and from each other, flanger wheels coacting with the heads, means for rotating the flanger heads, means for moving the flanger heads axially and cams on the flanger wheels to drive the last-named means.

In testimony whereof I have signed my name to this specification in the presence of two subscribing witnesses.
